UNITED STATES PATENT OFFICE.

JOHN R. HAMILTON, OF YONKERS, NEW YORK, ASSIGNOR TO AUTOMATIC SPRINKLER COMPANY OF AMERICA, OF NEW YORK, N. Y., A CORPORATION OF NEW YORK.

AUTOMATIC-SPRINKLER ALARM DEVICE.

1,289,455.

Specification of Letters Patent. Patented Dec. 31, 1918.

Application filed May 8, 1916. Serial No. 96,168.

To all whom it may concern:

Be it known that I, JOHN R. HAMILTON, a citizen of the United States, and resident of Yonkers, Westchester county, New York, 5 have made a certain new and useful Invention Relating to Automatic-Sprinkler Alarm Devices, of which the following is a specification, taken in connection with the accompanying drawing, which forms part of the 10 same.

This invention which involves improvements on the patents to Thompson, 743,049, of November 3, 1903, and Thompson and Hamilton, 1,022,446, of April 9, 1912, relates 15 to alarm valve devices which are adapted to be used in automatic sprinkler systems so as to give an alarm when the system comes into emergency operation in the event of fire, or when the main check valve is otherwise 20 unseated, with a minimum possibility of giving a false alarm under water hammer or other conditions.

In the accompanying drawing showing in 25 a somewhat diagrammatic way an illustrative embodiment of this invention,

Figure 1 is a sectional elevation.

Fig. 2 is an enlarged transverse sectional detail taken along the line 2—2 in Fig. 1; and

30 Fig. 3 is an enlarged detail section showing part of the alarm gong mechanism.

In the illustrative arrangement shown in the drawings the main alarm valve casing 1 is adapted to be mounted in the riser or main 35 supply pipe of the automatic sprinkler or other automatic fire extinguishing system, the lower part 4 of this valve casing being connected as indicated to the lower section of the supply pipe while the upper part 2 of the valve casing may be connected in a similar 40 way to the upper part of the distributing system which may comprise automatic sprinkler heads or other suitable distributing devices. The valve seat 5 may be mounted in this casing so that the main or 45 check valve 6 may coöperate therewith, this check valve being preferably heavily weighted as by casting its metallic body full of lead, for instance, so that it will normally 50 tend to remain closed and exert by its weight any desired differential opening pressure (say, one pound more or less per square inch) when it begins to open. This check valve may as indicated be mounted by one or 55 more valve lugs, such as 32, secured to the

valve body and secured to the valve stem 7 indicated in Figs. 1 and 2 which may be pivotally mounted in any suitable way within the valve casing, the cover plate 3 of which may be removably bolted in place so as to 60 facilitate the assembly and inspection of the parts.

A discharge valve may be operatively connected in any way with the main check valve so as to open in unison therewith and thus 65 control various passages connected with the alarm mechanism. For this purpose the discharge valve 9 having if desired the yieldable facing 10 may be mounted on a valve arm 8 connected to the valve stem 7 to which the 70 main check valve 6 is connected. In this way the two valves move substantially in unison any slight backlash or looseness of parts and connections, allowing a little play so that in 75 connection with the yieldable facing of the discharge valve it is definitely seated under all conditions when the main check valve is substantially closed. To promote this action this discharge valve may have its connected stem 11 carried through an enlarged 80 or swiveling aperture in the end of the valve arm 8 and held thereon by the lock nuts 12, the lower face of this arm where it coöperates with the valve 9 being preferably 85 somewhat dished or rounded up so as to promote the self-adjusting action of this valve and its accurate coöperation with the discharge valve seat 13 below. As indicated 90 this discharge valve may be mounted within a valve housing 15 held in place as by the projecting flange indicated on the valve seat 13, the valve stem 7 projecting through a suitable aperture in this housing so as to operate the discharge valve without substantial 95 leakage from the main check valve chamber.

A suitable Venturi or jet device of any desired construction may be arranged in a bypass around the main check valve and for this purpose the Venturi casing 23 may be secured to the main valve casing 1 so as to 100 provide the injecting passage 17 and the receiving passage 18 communicating with the valve casing above and below the main check valve 6. The Venturi or jet device may comprise the injecting nozzle 26 and the co-operating or aligned receiving nozzle 25 mounted within this Venturi casing so as to 105 constitute together a suitable constricted Venturi tube or passage developing a pressure reduction or suction impulse at its con- 110

stricted throat when substantial flow takes place therethrough. This annular space or interval between the two nozzles at their reduced ends may communicate as indicated 5 with a suction space 24 in the casing and the suction passage 28 communicating with this space may be connected to any alarm operating means so as to actuate the same by the suction developed through any substantial 10 continued flow of liquid through this Venturi device. If desired, suitable screens may be arranged in connection with the nozzles such as the screen 19 which may be supported around the larger end of the receiving 15 nozzle as by fitting within the hole receiving the plug or cap 21 and a similar tubular screen 20 may be supported around the enlarged inlet end of the injecting nozzle in a generally similar way by coöperating 20 with a recess formed in the plug 33 screwed or otherwise held in position in the Venturi casing in line with these nozzles so as to facilitate their assembly and inspection. An automatic control valve such as 22 may 25 coöperate with this Venturi or jet device so as to automatically close and shut off discharge of liquid into the receiving passage and connected distributing system when the discharge valve opens. For this purpose a 30 restricted discharge passage, such as 31, may be formed in connection with the receiving nozzle or adjacent parts and coöperate with the discharge valve in such way as to be opened thereby and allow the discharge of 35 liquid therethrough and into a suitable waste connection when this discharge valve opens. A convenient and desirable, although not necessary arrangement for this purpose, is indicated in Figs. 1 and 2 as comprising the 40 waste pipe 16 which communicates with the main valve casing and with a waste tube 14 mounted therein so that its upper end coöperates with the discharge valve seat 13. The discharge passage 31 may be brought down 45 adjacent this valve seat so as to communicate with the annular space 119 between this waste tube and the valve seat 13 so that when the discharge valve is closed as shown in Figs. 1 and 2, there is no communication 50 between this discharge passage and the corresponding waste passage and pipe 16 while when the discharge valve is opened a predetermined amount of liquid from the Venturi device can flow through this restricted 55 discharge passage 31 and into the coöperating waste passage so as to be discharged from the system and thus maintain a constant amount of flow through the Venturi device so as to maintain a suction impulse 60 of predetermined amount in the connected suction space and passage 28. Thus under fire emergency conditions where only a single sprinkler head opens for instance, the flow of water from this single operating 65 sprinkler head can be taken care of through

the by-pass Venturi connection without substantial opening of the main check valve 6. This flow of the extinguishing liquid through the Venturi device causes a suction impulse therein which operates the alarm devices if 70 it continues for a predetermined time which is regulated by the retarding devices employed. In the event that the main check valve 6 is prevented from fully seating, whether by foreign matter, distortion, or by 75 any other means, thus no longer exerting a pressure on the water or creating a differential action, the operatively connected discharge valve 9 is, by reason of the construction and coöperation of the elements, opened, 80 thus allowing the escape of liquid through the restricted discharge passage 31 into the waste pipe 16. This causes a sufficient reduction of pressure in the receiving nozzle so that this pressure is less than the pressure 85 above the partly opened main check valve 6 and this automatically closes the control valve 22 so that thereafter the flow through the Venturi device is determined by the amount of flow which takes place 90 through this restricted discharge passage 31 and this can be made sufficient so as to give a substantially similar suction impulse and thus actuate the alarm device after practically the same time delay as in the other 95 case.

This suction impulse may be utilized in any suitable way to operate an electrical or mechanical alarm preferably in connection with retarding devices which may with advantage have a uni-directional action effecting a retarded movement of the alarm or controlling mechanism so as to give an alarm after this suction impulse has acted for the desired time while on discontinuance of the 105 suction impulse the parts are allowed to quickly return to their normal inactive position, thus more effectively minimizing the giving of water hammer or similar false alarms through surge action in the piping. 110 For this purpose a mercury float chamber may be connected to the suction passage and may, if desired, comprise a casing 36 formed with a suction chamber 93 and with a communicating float chamber 46 which may contain an iron or other float 47 supported in the mercury 41 or other suitable liquid. This suction chamber 93 may be provided with a suction opening or passage 34 communicating with the suction passage 28 115 through a manual shut-off valve or cock 29 if desired, and if desired a similar shut-off valve 30 may be interposed between the pressure or alarm supply passage 27 in the chamber 92 adjacent the injecting nozzle 120 and the opening 35 in the float chamber so that this liquid can by its flow or pressure operate suitable alarm devices when the alarm passage 53 is opened by movement 125 of the float valve 50 connected in any suit- 130

able way with the float 47. If desired this float valve which may have a suitable resilient facing 52 may be mounted in the valve lever 51 pivoted as by the pin 55 in a suitable bracket or bearing which may be conveniently formed on the tube constituting the alarm passage 53. A pivotal or other loose connection such as the pin 49 may connect this valve lever with the float 47 as 5 through the reduced neck or upper part 48 of the float so that when this float descends it draws the float valve away from the cooperating valve seat at the end of this alarm passage and allows the liquid from the 10 supply pipe to pass through this passage to operate any electric or mechanical alarm device. This action takes place when the mercury or other liquid 41 is transferred to a sufficient extent by the suction action 15 described from the float chamber 46 to the suction chamber 93. In this connection the communicating transfer passage 45 may be provided at any suitable point with a retarder valve preferably retarding the transfer of the mercury into the suction chamber 20 while allowing its much more rapid and free movement in the opposite direction. In order to minimize joints and possible leakage in the lower part of this mercury casing 25 30 below the surface of the mercury therein this retarder valve is preferably mounted within a retarder valve casing 40 which may be supported as by the screw connection indicated at its upper end with the adjacent part of 35 the casing. This retarder valve casing may comprise adjacent its lower portion a valve seat with which coöperates the retarder valve 43 whenever it rises into the closed position indicated so that under these 40 conditions the restricted retard passage 114 through this valve restricts the transfer of mercury between the float and suction chambers under the suction impulse caused by the Venturi device so that the desired time interval takes place after the commencement 45 of discharge of liquid from one of the distributing devices before the mercury flow opens the float valve or otherwise causes the actuation of the connected alarm mechanism, while as soon as this suction impulse 50 ceases and the mercury tends by its unbalanced weight to flow back into the float chamber this retarder valve is free to fall and thus open a considerably increased passage 55 for the mercury through the central bore or passage 94 in this retarder valve casing and the holes 42 may be made around the periphery of its lower part preferably above the cap 44 which may be screwed into this 60 valve casing to support and guide the valve in operative position therein preferably at the lower portion of the extension 39 of the suction chamber. As indicated a cap such as 37 may be screwed on this casing above 65 and in line with the retarder valve casing so as to facilitate its mounting and a larger cap plate 64 may be bolted or otherwise secured above the float chamber so as to allow the described parts to be mounted therein. It is also desirable to arrange for the drainage of liquid from the alarm pipe 61 upon the discontinuance of alarm, and for this purpose a drain chamber 54 may be formed in this casing and the drain pipe 58 connected thereto, a reduced drain aperture such as 70 75 57 being arranged in this drain connection so as to allow a limited amount of drainage which is ample to take care of any slight leakage past the valves and parts while entirely insufficient to substantially interfere 80 with the regular alarm indications caused under fire emergency conditions. If desired, a screen, such as 59, may be provided around the alarm passage 53 so as to prevent any dirt or scale passing into the alarm mechanism and a cap or plug 60 may be arranged in the casing to coöperate with this screen and another cap 56 may if desired be provided adjacent the bottom of this drain chamber. 85 90

An alarm pipe 61 connected with the alarm passage 53 in any suitable way may transmit the flow or pressure of the liquid to the alarm devices under emergency conditions and any suitable electric alarm may 95 be used in this connection, such, for example, as a diaphragm chamber 65 diagrammatically indicated as being provided with a diaphragm 68 with which coöperate the insulated electric alarm contact 67 and its pivoted or movable extension 68 coöperating with the diaphragm so as to be raised by the diaphragm into electric contact with the co-operating contact 69 also insulated in the casing cover. These two contacts may as indicated be in circuit with a suitable battery or other source of electricity 71 and with the electric bell or alarm 70 of any suitable description. Thus when the liquid from the alarm pipe 61 and connection 62 raises this 100 diaphragm sufficiently the electric alarm is operated through the connections described. 105

A suitable mechanical or water motor alarm may also be operated under these conditions through the pipe 63 which may communicate with a suitable motor nozzle 76 preferably arranged adjacent the lower part of the motor casing 79 and provided with a suitable screen, such as 72, around the inlet end of the nozzle forming the chamber 73. 110 The curved and perforated deflector shield 74 may be supported in any way around the screen 72 so as to deflect toward the bottom of the motor casing particles of dirt, etc., while the water passing around the upper 115 ends of this shield enters the annular space 75 and passes freely through the screen 72 to supply the nozzle 76. This nozzle is of course pointed upward sufficiently so that its jet engages the Pelton type or other 120 125 130

buckets 77 on the motor wheel mounted within the casing as on the motor shaft 78, the water being discharged through a suitable waste pipe or connection 90 communicating with the lower part of the motor casing which is preferably divided into two parts substantially above the motor shaft so that this shaft and its bearings are permanently mounted in the lower casing section as indicated, and are not wedged or cramped when the upper casing section is secured in position. It is also desirable to provide for the accurate support and alinement of this motor in connection with the gong or other mechanical alarm device which is usually mounted on the outside of the outer wall 81 of the building and this may be conveniently effected by securing the gong support 87 to the outer face of this wall as by suitable expansion bolts indicated and rigidly securing to this gong support an alining connector tube 80 which may be screwed into a flange or collar 116 on the support and extend entirely through the wall so as to provide a substantially rigid alining projection with which may coöperate the apertured collar 116 formed on the motor bracket 82 connected to the motor casing. This motor bracket may be secured on the connector tube as by the securing nut 110 screwed on the tube for instance, so as to permanently lock these parts in position and insure the alinement of the motor and connected operating mechanism for the gong. As indicated more in detail in Fig. 3, the hammer arms 83 may be rigidly secured to the tubular gong shaft 89 revolubly mounted in the bearing 108 in the gong support which may, if desired, be provided with suitable anti-friction or roller bearings held in place as by the bearing cap 104. The inner end of this tubular gong shaft may be provided with a coupling device such as the block 107 to which may be secured as by the screws 106 the steel or other coupling washer 105 which may be formed with a square or other non-circular hole adapted to coöperate with the alarm shaft 109. The inner end of this alarm shaft may coöperate with a similarly shaped aperture 100 formed in the coupling 99 on the motor shaft and preferably so shaped as to allow a limited angular bending of this alarm shaft so as to have some universal joint action in connection therewith. In assembling these parts the alarm shaft may be inserted from the outside of the building so that its inner end properly coöperates with the coupling aperture 100 and then this square or other non-circular shaft or rod may be cut off at such length as to be substantially flush with the outside of the tubular gong shaft 89 and permanently held in position in connection therewith as by the cap 103 screwed over the end of this shaft. The gong 84 which may be con-

veniently bolted or mounted on the gong casing 85 may then be put in place as by slipping the holding flange 111 at the upper end of this gong casing over the corresponding locking member of the gong support so that the lower locking portion 112 of this gong casing coöperates with the projecting locking lug 86 of the support so as to be padlocked or permanently secured thereon and firmly hold the gong in operative position. The coöperating gong hammers are preferably in the form of hammer rings 88 loosely mounted on the hammer pins 102 so as to coöperate with the upper part of the gong when the motor is running at normal speed and thus give a strong blow to the gong when the hammers are thrown outward by centrifugal action, while at the same time their weight and rebound action tend to effectively clear them from the gong and prevent deadening the alarm signal produced, and also the motor is left entirely free to start and attain practically full speed before the hammers engage the gong at all so as to exert any retarding action on the motor or driving connections.

This invention has been described in connection with a number of illustrative embodiments, parts, forms, sizes, proportions, materials and arrangements, to the details of which disclosure the invention is not of course to be limited, since what is claimed as new and what is desired to be secured by Letters Patent is set forth in the appended claims:

1. In sprinkler alarm devices, a supply pipe, connected with an automatic sprinkler distributing system, a connected valve casing, a main check valve mounted in said valve casing, a discharge valve mounted within a valve housing located within said casing and operatively connected to said main check valve, a Venturi casing secured to said valve casing and comprising an opposed injecting nozzle and coöperating receiving nozzle forming a by-pass Venturi passage around said main check valve, an automatic control valve coöperating with and vertically mounted above the end of said receiving nozzle to prevent entrance of liquid into said nozzle from said distributing system, there being a suction space communicating with the restricted throat of said Venturi passage, a restricted discharge passage communicating with said receiving nozzle and controlled by said discharge valve, a valve seat with which said discharge valve coöperates and having a connection with said discharge passage, a tube mounted within said valve seat to be normally closed by said discharge valve, a coöperating waste passage communicating with said tube to be placed in communication with said discharge passage when said discharge valve opens, a float casing comprising a float chamber and

a suction chamber having their lower portions substantially imperforate and connected by a transfer passage, a unidirectional retard device comprising a tubular valve casting supported at its upper end in communication with said suction chamber and a retarder valve mounted within said valve casting within said transfer passage and automatically closing to provide a restricted retard passage for the transfer of liquid from said float chamber to said suction chamber, a connection between said suction chamber and the suction space of said Venturi casing, a charge of mercury and a float in said float chamber, a float valve connected to said float and controlling an alarm passage receiving liquid from said supply pipe and alarm devices connected to said alarm passage to give an alarm when said alarm passage is opened.

2. In sprinkler alarm devices, a supply pipe connected with an automatic sprinkler distributing system, a connected valve casing, a main check valve mounted in said valve casing, a discharge valve mounted within a valve housing located within said casing and operatively connected to said main check valve, a Venturi casing secured to said valve casing and comprising an opposed injecting nozzle and coöperating receiving nozzle forming a by-pass Venturi passage around said main check valve, an automatic control valve coöperating with and vertically mounted above the end of said receiving nozzle to prevent entrance of liquid into said nozzle from said distributing system, there being a suction space communicating with the restricted throat of said Venturi passage, a restricted discharge passage communicating with said receiving nozzle and controlled by said discharge valve, a valve seat with which said discharge valve coöperates and having a connection with said discharge passage, a float casing comprising a float chamber and a suction chamber having their lower portions connected by a transfer passage, a unidirectional retard device to provide a restricted retard passage for the transfer of liquid from said float chamber to said suction chamber, a connection between said suction chamber and the suction space of said Venturi casing, a charge of mercury and a float in said float chamber, a float valve connected to said float and controlling an alarm passage receiving liquid from said supply pipe and alarm devices connected to said alarm passage to give an alarm when said alarm passage is opened.

3. In sprinkler alarm devices, a supply pipe connected with an automatic sprinkler distributing system, a connected valve casing, a main check valve mounted in said valve casing, a discharge valve mounted within a valve housing located within said casing and operatively connected to said

main check valve and mounted on the same valve stem to move substantially in unison therewith, a Venturi casing secured to said valve casing and comprising an opposed injecting nozzle and coöperating receiving nozzle forming a by-pass Venturi passage around said main check valve, an automatic control valve coöperating with and vertically mounted above the end of said receiving nozzle to prevent entrance of liquid into said nozzle from said distributing system, a restricted discharge passage communicating with said receiving nozzle and controlled by said discharge valve, a valve seat with which said discharge valve coöperates and having a connection with said discharge passage, a tube mounted within said valve seat to be normally closed by said discharge valve, and a coöperating waste passage communicating with said tube to be placed in communication with said discharge passage when said discharge valve opens.

4. In sprinkler alarm devices, a supply pipe connected with an automatic sprinkler distributing system, a connected valve casing, a main check valve mounted in said valve casing, a discharge valve mounted within a valve housing located within said casing and operatively connected to said main check valve and mounted on the same valve stem to move substantially in unison therewith, a Venturi casing secured to said valve casing and comprising an opposed injecting nozzle and coöperating receiving nozzle forming a by-pass Venturi passage around said main check valve, an automatic control valve coöperating with said receiving nozzle to prevent entrance of liquid into said nozzle from said distributing system, and a restricted discharge passage communicating with said receiving nozzle and controlled by said discharge valve.

5. In sprinkler alarm devices, a supply pipe connected with an automatic sprinkler distributing system, a connected valve casing, a main check valve mounted in said valve casing, a discharge valve operatively connected to said main check valve, a Venturi casing secured to said valve casing and comprising an opposed injecting nozzle and coöperating receiving nozzle forming a by-pass Venturi passage around said main check valve, an automatic control valve coöperating with said receiving nozzle to prevent entrance of liquid into said nozzle from said distributing system, and a restricted discharge passage communicating with said receiving nozzle and controlled by said discharge valve.

6. In sprinkler alarm devices, a suction jet device to be connected with an automatic sprinkler distributing system, a connected float casing comprising a float chamber and a suction chamber having their lower portions substantially imperforate

and connected by a transfer passage, a unidirectional retard device comprising a tubular valve casing supported at its upper end in communication with said suction chamber and a retarder valve mounted within said valve casing within said transfer passage and automatically closing to provide a restricted retard passage for the transfer of liquid from said float chamber to said suction chamber, a charge of mercury and a float in said float chamber, a float valve connected to said float and controlling an alarm passage receiving liquid from said supply pipe and alarm devices connected to said alarm passage to give an alarm when said alarm passage is opened.

7. In sprinkler alarm devices, a suction jet device to be connected with an automatic sprinkler distributing system, a connected float casing comprising a float chamber and a suction chamber having their lower portions substantially imperforate and connected by a transfer passage, a retard device comprising a tubular valve casing and a retarder valve mounted within said valve casing within said transfer passage and automatically closing to provide a restricted retard passage for the transfer of liquid from said float chamber to said suction chamber, a charge of water immiscible liquid and a float in said float chamber, a float valve connected to said float and controlling an alarm passage adapted to receive liquid from the supply pipe connected to said distributing system and alarm devices connected to said alarm passage to give an alarm when said alarm passage is opened.

8. In sprinkler alarm devices, a valve casing to be connected with an automatic sprinkler distributing system, a main check valve mounted in said valve casing, a discharge valve operatively connected to said main check valve to be actuated thereby, a Venturi device comprising an opposed injecting nozzle and coöperating receiving nozzle forming a by-pass Venturi passage around said main check valve, an automatic control valve coöperating with said receiving nozzle to prevent entrance of liquid into said nozzle from said distributing system, there being a suction space communicating with the restricted throat of said Venturi passage, a restricted discharge passage communicating with said receiving nozzle and controlled by said discharge valve and alarm actuating mechanism comprising a unidirectional retard device and having a valved connection with said Venturi device.

60 9. In sprinkler alarm devices, a valve casing to be connected with an automatic sprinkler distributing system, a main check valve mounted in said valve casing, a discharge valve operatively connected to said

main check valve to be actuated thereby, a 65 Venturi device comprising an opposed injecting nozzle and coöperating receiving nozzle forming a by-pass Venturi passage around said main check valve, there being a suction space communicating with the restricted throat of said Venturi passage, a restricted discharge passage communicating with said receiving nozzle and controlled by said discharge valve and alarm actuating mechanism comprising a unidirectional retard device and having a connection with 70 said Venturi device.

10. In sprinkler alarm devices, a valve casing to be connected with an automatic sprinkler distributing system, a main check 80 valve mounted in said valve casing, a discharge valve operatively connected to said main check valve to be actuated thereby, a Venturi device comprising an opposed injecting nozzle and coöperating receiving 85 nozzle forming a by-pass Venturi passage around said main check valve, a restricted discharge passage communicating with said receiving nozzle and controlled by said discharge valve, and alarm actuating mechanism 90 comprising a retard device and having a connection with said Venturi device.

11. In sprinkler alarm devices, a valve casing to be connected with an automatic sprinkler distributing system, a weighted 95 main check valve mounted in said valve casing, a discharge valve operatively connected to said main check valve to move substantially in unison therewith, a Venturi jet device comprising an opposed injecting nozzle and coöperating receiving nozzle forming a by-pass passage around said main check valve, an automatic control valve co-operating with said receiving nozzle to prevent entrance of liquid into said nozzle 105 from said distributing system, a restricted discharge passage controlled by said discharge valve and receiving liquid passing through said Venturi jet device, alarm actuating mechanism comprising a unidirectional retard device and connected with said Venturi jet device, and an alarm device connected to said alarm actuating mechanism.

12. In sprinkler alarm devices, a valve casing to be connected with an automatic 115 sprinkler distributing system, a weighted main check valve mounted in said valve casing, a discharge valve operatively connected to said main check valve, a Venturi jet device comprising an opposed injecting nozzle and coöperating receiving nozzle forming a by-pass passage around said main check valve, an automatic control valve co-operating with said receiving nozzle to prevent entrance of liquid into said nozzle from 120 said distributing system, a restricted discharge passage controlled by said discharge valve and receiving liquid passing through 125

said Venturi jet device, alarm actuating mechanism connected with said Venturi jet device, and an alarm device connected to said alarm actuating mechanism.

- 5 13. In sprinkler alarm devices, a valve casing to be connected with an automatic sprinkler distributing system, a main check valve mounted in said valve casing, a discharge valve operatively connected to said
10 main check valve, a Venturi jet device forming a by-pass passage around said main check valve, a restricted discharge passage controlled by said discharge valve and receiving liquid passing through said Venturi
15 jet device, alarm actuating mechanism connected with said Venturi jet device and an alarm device connected to said alarm actuating mechanism.
14. In sprinkler alarm devices, a valve casing to be connected with an automatic 20 sprinkler distributing system, a main check valve mounted in said valve casing, a discharge valve operatively connected to said main check valve, a suction jet device forming a by-pass passage around said main check valve, a restricted discharge passage controlled by said discharge valve and receiving liquid passing through said suction jet device, and alarm actuating mechanism connected with said suction jet device.

- 25 15. In sprinkler alarm devices, a valve casing to be connected with an automatic sprinkler distributing system, a main check valve mounted in said valve casing, a Venturi jet device mounted on said casing and forming a by-pass passage around said main check valve, means comprising a discharge valve controlled by said check valve and a restricted discharge passage governed thereby and communicating with said Venturi jet device to effect a substantially predetermined flow through said Venturi jet device when

said check valve is open, and retarding alarm actuating mechanism connected with said Venturi jet device.

45

16. In sprinkler alarm devices, a valve casing to be connected with an automatic sprinkler distributing system, a main check valve mounted in said valve casing, a Venturi jet device forming a by-pass passage 50 around said main check valve, means comprising a restricted discharge passage communicating with said Venturi jet device to effect a substantially predetermined flow through said Venturi jet device when said 55 check valve is open, and retarding alarm actuating mechanism connected with said Venturi jet device.

17. In sprinkler alarm devices, a valve casing to be connected with an automatic 60 sprinkler distributing system, a main check valve mounted in said valve casing, a suction jet device forming a by-pass passage around said main check valve, means comprising a discharge valve controlled by said 65 check valve and a restricted discharge passage governed thereby to effect a substantially predetermined flow through said suction jet device when said check valve is open.

70

18. In sprinkler alarm devices, a valve casing to be connected with an automatic sprinkler distributing system, a main check valve mounted in said valve casing, a suction jet device forming a by-pass passage 75 around said main check valve, and means controlled by said check valve to effect a substantially predetermined flow through said suction jet device when said check valve is open.
